UNITED STATES PATENT OFFICE.

PAUL J. BELLAVANCE, OF ATTLEBORO, MASSACHUSETTS, ASSIGNOR OF ONE-HALF TO
JOSEPH E. GALLANT, OF ATTLEBORO, MASSACHUSETTS.

SEPARABLE BUTTON.

Application filed March 5, 1925. Serial No. 13,207.

To all whom it may concern:

Be it known that I, PAUL J. BELLAVANCE, a citizen of the United States, residing at Attleboro, in the county of Bristol and State 5 of Massachusetts, have invented certain new and useful Improvements in Separable Buttons, of which the following is a specification.

My invention relates to separable buttons, and specifically comprises a separable button 10 having cooperating male and female members having means thereon to lock said members on insertion of the stem of the male member within the socket of the female member thereof and means operable on further pressing together and releasing the said members to release said locking means to permit separation of said members. So far as I am aware, no one has heretofore provided a separable button which will release the locking means thereof on further pressing together and releasing the coacting male and female members. The main objects of my invention is to provide a separable button of this type.

25 A further object of my invention is to provide a separable button which may be unlocked and locked by the mere operation of pressing and pulling on the bases of the cooperating male and female members 30 thereof. Where my invention is employed as a separable cuff button, it is obvious, therefore, that to lock or unlock the members thereof, it is not necessary to insert the fingers between the cuffs to dirty them.

35 A further object of my invention is to provide a separable button which can be locked or unlocked in the dark.

40 A further object of my invention is to provide a separable cuff button having no projecting levers or parts on the members thereof to catch in or tear the cuffs.

45 A further object of my invention is to provide a separable cuff button having no long longitudinally projecting stem, making insertion in the cuffs a difficult operation.

50 A further object of my invention is to provide a separable cuff button having no nobs or projecting parts on the bases of the cooperating members thereof to interfere with the placing of the usual, desirable designs thereon.

These and such other objects of my invention as may hereinafter appear will be best understood from a description of one em-

bodiment thereof, such as is illustrated in 55 the accompanying drawings.

In the drawings, Fig. 1 is a side elevation of a separable cuff button embodying my invention in locked position.

Fig. 2 is a longitudinal sectional view of 60 a separable cuff button embodying my invention in locked position, a portion of the female member being shown in elevation.

Fig. 3 is a longitudinal sectional view, 65 partly shown in elevation, of a separable cuff button employing my invention after the coacting male and female members thereof have been further pressed together to start the functioning of the means I employ to 70 release the locking means.

Fig. 4 is a longitudinal sectional view, partially shown in elevation, of the co-operating male and female members of a 75 separable button employing my invention, after the means I employ to release the locking means thereof has functioned to release said means to permit further manual separation of said members.

Fig. 5 is a longitudinal sectional view, 80 partly shown in elevation, of the co-operating male and female members of my invention in detached, unlocked position.

Fig. 6 is a cross sectional view taken along the line 6—6 of Fig. 5, showing the preferred type of locking spring means I employ.

In the drawings, wherein like characters of reference indicate like parts throughout, 90 10 generally represents a separable cuff button made in accordance with my invention. 12 generally indicates the female member of my invention and 14 the male member thereof. In the description and claims, I refer to the relative parts of said 95 members in the locked position shown in the drawing with male member underneath.

As stated, the cooperating male and female members 12 and 14 have means thereon to lock said members together on insertion of the stem of the male member thereof within the socket of the female member and also have means thereon operable on further pressing together and releasing of said members to release said locking means to permit 100 105 separation of said members.

To provide the male and female members 12 and 14 respectively, with said respective means, I prefer-

ably construct them as follows: The female member 12 comprises the base 16 which may be ornamented in any suitable fashion, if desired, the shank 18, which is preferably hollow, projecting therefrom and terminating in the head 20. The head 20 in my preferred embodiment is preferably made in flat, cylindrical shape, is preferably provided with a central female socket opening 22, and preferably contains the locking spring 24, non-rotatably mounted therein surrounding the female portion thereof. The hollow head 20 is preferably provided with the washer 26 firmly seated therein having the points 28 struck up therefrom to space the washer 26 from the upper disk 21 of the head 20. Said washer 26 is provided with a sleeve 30 projecting upwards a short distance therefrom provided with diametrically opposed segmental slits 32 on the periphery thereof. The preferred embodiment of spring locking means employed comprises the U-shaped hair-pin spring 24 mounted within said segmental grooves 32. As in similar former constructions, the sides 34 of said U-shaped spring are adapted to expand to permit insertion of the stem of the male member through the female opening 22 and within the hollow shank 18 of the female member, and are adapted to contract to fit within a groove, slits, or other means employed for this purpose on the stem of the male member to retain said members together (Fig. 6). Though I have shown a U-shaped locking spring in my preferred embodiment, it is obvious that any other type of locking means, preferably spring locking means, may be employed suitably mounted in any suitable part of the female member adjacent to the female portion thereof.

The male portion of my invention preferably comprises the base 40 which may be ornamented in any suitable fashion, if desired, and has the usual rigid stem 42 suitably mounted therein, preferably on the base 40 thereof. In my preferred embodiment, I also preferably rigidly secure the hollow shank section 44 on the base thereof and I mount thereon the head 46, which is also preferably flat and provided with a central opening 47, of appreciably larger diameter than said rigid stem 42, and the sleeve 48 preferably rigidly secured to said flat head portion 50 projecting downwards therefrom and slidable on said hollow shank 44, preferably within. These telescoping members, the rigid shank 44 and the slidable sleeve head section 48 are preferably provided with means thereon to limit the upward movement of the slidable sleeve section 48, in my preferred embodiment this means preferably comprising the outwardly projecting annular lip 52 on the lower end of the slidable shank 48 and inwardly projecting stop lip 54 on the upper end of the rigid

shank section 44. The stem 42, which as stated is preferably rigidly mounted on the base 40, extends through said hollow shank and sleeve above said head 50. The portion above said head is preferably enlarged as at 56, the enlargement 56 in my preferred embodiment preferably comprising the cap 56 mounted on the upper end thereof terminating in the annular lower edge 58 which may be beveled, if desired, and also, if desired, offset from said rigid stem as at 60. The stem 42 is provided with a stop 62, a substantial distance below the lower edge 58 of said cap. In my preferred embodiment said stop 62 preferably comprises the lugs 62 struck up from the sides of said stem 42. It is obvious that on insertion of the stem of the male member the sides 34 of the locking spring 24 may register below the enlarged head 56 of the rigid stem 42 to secure the cooperating male and female members 12 and 14 together.

I will now describe the specific means I employ to release said locking means 24 from the stem of the male member to permit separation of said members. In my preferred embodiment said means preferably comprises a slidable sleeve 64 loosely mounted on the stem 42 between said cap 56 and stop 62. In my preferred embodiment said slidable sleeve is also preferably provided with an annular ridge 66 projecting substantially centrally from the periphery thereof. As will be apparent later, particularly if the locking spring means 24 is of a substantial strength, said ridge 66 may be omitted. To cooperate with said slidable sleeve 64, as a means to release the locking means 24, I preferably also provide the ejection spring 68, in my preferred embodiment said ejection spring 68 preferably comprising the helical spring 68 having the base thereof abutting the base 40 of said male member and the top thereof abutting the lower edge 70 of the slidable head sleeve 48. Though said ejection spring is a highly desirable feature of my invention, it may be omitted, as a strong spring 24 alone will raise up the slidable sleeve 64 to close the groove 72, normally formed between the lower edge 58 of the enlarged portion 56 of the stem 42 and the annular ridge 66 on the slidable sleeve or upper edge of said sleeve if said ridge 66 is omitted, as the members are pulled apart.

The operation of my invention is obvious from the above description. To detachably secure or lock the cooperating male and female members 12 and 14 of my invention together, it is obvious that on insertion of the stem 42 of the male member within the female portion 22 and hollow shank 18 of the female member, the sides 34 of the locking spring 24 will expand to permit the insertion of the enlarged head 56 of said

stem therein as shown in dotted lines in Fig. 6. When the enlarged head of said stem has passed by the sides 34 of the locking spring 24, it is obvious that they will contract within the groove 72 formed between the lower edge 58 of the enlarged head 56 and the upper end of the slidable sleeve 64 or upper edge of the annular ridge 66 thereon where said annular ridge 66 is employed, thereby locking said male and female members together. As the stem 42 is inserted slowly into the female portion 22, it is obvious that the contacting sides 34 of the locking spring 24 will push the slidable sleeve 64 downwards on the stem 42 to form the groove 72. As shown in Fig. 2, it is obvious that in this locking operation the slidable sleeve 48 of the head 46 of the male member will be slightly depressed against the pressure of the ejection spring 68, thereby requiring a slight pressure between the bases of the said members to lock them. In this position, however, the pressure of the spring 68 tending to push up the slidable head 46 of the male member 14 and adjacent female member 12, will cause the sides 34 of the locking spring 24 in the groove 72 to firmly bind against the lower edge 58 of the enlarged head 56 to firmly secure said members together. It is obvious that when in this locked position the sleeve 64 will remain in lowered position.

To unlock said members further press the bases 16 and 40 of said members together between the fingers, and the parts will take the position shown in Fig. 3, the ejection spring 68 being fully compressed and the slidable sleeve 48 sliding down to its lowest position within the hollow shank 44 of the male member. During this compression of said members, it is obvious that the lower edge of the slidable sleeve 64 will abut the top 62 on the rigid stem 42, thus limiting the downward movement of said sleeve. As the head 20 of the female member and attached spring 24 are forced downward in this operation, it is obvious that the sides 34 of the locking spring 24 will be forced downwards out of the groove 72 and over the annular ridge 66 on the slidable sleeve 64 where employed, or down to impinge upon the periphery of the slidable sleeve 64 where not employed, as shown in Fig. 3. When pressure is then taken off the bases 16 and 40 of said co-operating members, it is obvious that the ejection spring 68 will force the slidable sleeve 48 of the head of the male member, and the head 20 of the female member upwards, the head of the female member carrying with it the locking spring 24. The compressing sides 34 of the locking spring lying underneath the annular ridge 66 on the slidable sleeve 64, or impinging upon said sleeve 64 will carry said sleeve upwards until the upper edge of

said annular ridge 66 or the upper edge of said slidable sleeve 64 where said ridge 66 is not employed abuts the lower edge 58 of the enlarged head portion 56 of said stem 42, thereby completely closing up the groove 72. On further upward pressure of said ejection spring 68, the slidable sleeve 64 being now limited in its upward movement, it is obvious that the sides 34 of the hairpin spring 24 will slide over the annular ridge 66 and onto the periphery of the enlarged upper portion 56 of said rigid stem 42, thereby releasing the unlocking means and permitting said members to be further separated by hand as shown in Fig. 4. Fig. 4, therefore, represents an instantaneous view taken before the force of gravity has had a chance to act on the slidable sleeve 64 to re-open the groove 72. Fig. 5 represents a view of the cooperating male and female members after they are completely unlocked and detached from each other. Where the ejection spring 68 is omitted, it is obvious that my invention will function in its unlocking features in similar fashion after said members are manually pulled quickly apart.

Though my invention is shown as specifically applied to a separable cuff button, it is obvious that it may function with other types of separable buttons and is especially useful in separable buttons employed for attaching the side curtains of automobiles. It is obvious that the shanks may be round as shown, square, or of any suitable shape.

It is obvious that I have provided a construction which will function to lock said members on mere insertion of the stem of the male member within the socket of the female member and a construction which is adapted to permit separation of said members by a mere further pressing together thereof and the releasing thereof with the attendant advantages set forth in the introduction to this application.

It is understood that my invention is not limited to specific embodiment shown and that various deviations may be made therefrom without departing from the spirit and scope of the appending claims.

What I claim as new and desire to secure by Letters Patent is:

1. A separable button, comprising a pair of male and female coacting members, the female member comprising a base, a hollow shank and a flat head having a central socket opening and a U-shaped locking spring member non-rotatably contained therein, and the male member comprising a base, a hollow shank, a flat head having a central opening and an integral annular sleeve projecting downwards therefrom slidably within said shank having means thereon adapted to abut a stop on said shank to limit its upward movement, a stem mounted on said base extending through said shank and

sleeve above said head having a cap mounted thereon terminating in an annular lower edge offset from said stem and a stop on the periphery thereof below said cap, an ejection spring extending between said base and the lower edge of the head sleeve and a sleeve slidable on said stem between said cap and stop having an annular ridge projecting substantially centrally from the periphery thereof, whereby on insertion of said female member on said male member and pressing said members together the sides of the U-shaped locking spring may register within the groove formed on said stem between the lower cap edge and upper edge of the annular ridge on the slidable sleeve to retain said members together, on further pressing together of said members and consequent depression of said ejection spring, the sides of the U-shaped locking spring may ride over the annular ridge on the slidable stem to impinge upon the lower periphery of said stem sleeve, on release of pressure said ejection spring may cause the gripping sides of the U-shaped locking spring to carry said slidable stem sleeve upwards to close said groove, and on further pressure of said ejection spring the sides of said U-shaped locking spring may slide over said annular sleeve ridge and closed groove to abut the periphery of the cap stem to release said members.

2. A separable button, comprising a pair of male and female coacting members, the female member comprising a base, a hollow shank and a flat head having a central socket opening and a U-shaped locking spring member non-rotatably contained therein, and the male member comprising a base, a hollow shank, a flat head having a central opening and an integral annular sleeve projecting downwards therefrom slidable within said shank having means thereon adapted to abut a stop on said shank to limit its upward movement, a stem mounted on said base extending through said shank and sleeve above said head having a cap mounted thereon terminating in an annular lower edge offset from said stem and a stop on the periphery thereof below said cap, an ejection spring extending between said base and the lower edge of the head sleeve and a sleeve slidable on said stem between said cap and stop having an annular ridge projecting substantially centrally from the periphery thereof.

3. A separable button, comprising a pair of male and female coacting members, the female member comprising a base, a hollow shank and a head having a central socket opening and a U-shaped locking spring member non-rotatably contained therein, and the male member comprising a base, a hollow shank, a head having a central opening and an annular sleeve projecting downwards therefrom slidable on said stem between said cap and stop having an annular ridge projecting substantially centrally from the periphery thereof.

wards therefrom slidable on said shank, a stem mounted on said shank extending above said head having a cap mounted thereon terminating in an annular lower edge and a stop on the periphery thereof below said cap, an ejection spring abutting the lower edge of the head sleeve and a sleeve slidable on said stem between said cap and stop, whereby on insertion of said female member on said male member and pressing said members together the sides of the U-shaped locking spring may register within the groove formed on said stem between the lower cap edge and upper edge of the slidable sleeve to retain said members together, on further pressing together of said members and consequent depression of said ejection spring, the sides of the U-shaped locking spring may impinge upon the lower periphery of said stem sleeve, on release of pressure said ejection spring may cause the gripping sides of the U-shaped locking spring to carry said slidable stem sleeve upwards to close said groove, and on further pressure of said ejection spring the sides of said U-shaped locking spring may slide over said closed groove to abut the periphery of the cap stem to release said members.

4. A separable button, comprising a pair of male and female coacting members, the female member comprising a base, a hollow shank and a head having a central socket opening and a U-shaped locking spring member non-rotatably contained therein, and the male member comprising a base, a hollow shank, a head having a central opening and an annular sleeve projecting downwards therefrom slidable on said shank, a stem mounted on said shank extending above said head having a cap mounted thereon terminating in an annular lower edge and a stop on the periphery thereof below said cap, an ejection spring abutting the lower edge of the head sleeve and a sleeve slidable on said stem between said cap and stop.

5. A separable button, comprising a pair of male and female coacting members, the female member comprising a base, a hollow shank and a flat head having a central socket opening and a locking spring member non-rotatably contained therein, and the male member comprising a base, a hollow shank, a flat head having a central opening and an integral annular sleeve projecting downwards therefrom slidable within said shank having means thereon adapted to abut a stop on said shank to limit its upward movement, a stem mounted on said base extending through said shank and sleeve above said head having a cap mounted thereon terminating in an annular lower edge offset from said stem and a stop on the periphery thereof below said cap, an ejection spring extending between said base and the lower edge of the head sleeve, and

- a sleeve slidable on said stem between said cap and stop having an annular ridge projecting substantially centrally from the periphery thereof, whereby on insertion of 5 said female member on said male member and pressing said members together the locking spring may register within the groove formed on said stem between the lower cap edge and upper edge of the annular ridge on the slidable sleeve to retain 10 said members together, on further pressing together of said members and consequent depression of said ejection spring, the locking spring may ride over the annular ridge on 15 the slidable stem to impinge the lower periphery of said stem sleeve, on release of pressure said ejection spring may cause the locking spring to carry said slidable stem sleeve upwards to close said groove, and 20 on further pressure of said ejection spring the locking spring may slide over said annular sleeve ridge and closed groove to abut the periphery of the cap stem to release said members.
- 25 6. A separable button, comprising a pair of male and female coacting members, the female member comprising a base, a hollow shank and a flat head having a central socket opening and a locking spring member 30 non-rotatably contained therein, and the male member comprising a base, a hollow shank, a flat head having a central opening and an integral annular sleeve projecting downwards therefrom slidable within said 35 shank having means thereon adapted to abut a stop on said shank to limit its upward movement, a stem mounted on said base extending through said shank and sleeve above said head having a cap mounted 40 thereon terminating in an annular lower edge offset from said stem and a stop on the periphery thereof below said cap, an ejection spring extending between said base and the lower edge of the head sleeve and a 45 sleeve slidable on said stem between said cap and stop having an annular ridge projecting substantially centrally from the periphery thereof.
7. A separable button, comprising a pair 50 of male and female coacting members, the female member comprising a base, a hollow shank and a head having a central socket opening and a locking spring member non-rotatably contained therein, and the 55 male member comprising a base, a hollow shank, a head having a central opening and an annular sleeve projecting downwards therefrom slidable on said shank, a stem mounted on said shank extending above said 60 head having a cap mounted thereon terminating in an annular lower edge and a stop on the periphery thereof below said cap, an ejection spring abutting the lower edge of the head sleeve and a sleeve slidable on said 65 stem between said cap and stop, whereby on insertion of said female member on said male member and pressing said members together the locking spring may register within the groove formed on said stem between the lower cap edge and upper edge of the slid- 70 able sleeve to retain said members together, on further pressing together of said members and consequent depression of said ejection spring, the locking spring may impinge upon the lower periphery of said stem 75 sleeve, on release of pressure said ejection spring may cause the locking spring to carry said slidable stem sleeve upwards to close said groove, and on further pressure of said ejection spring said locking spring 80 may slide over said closed groove to abut the periphery of the cap stem to release said members.
8. A separable button, comprising a pair of male and female coacting members, the 85 female member comprising a base, a hollow shank and a head having a central socket opening and a locking spring member non-rotatably contained therein, and the male member comprising a base, a hollow shank, a head having a central opening and an annular sleeve projecting downwards therefrom slidable on said shank, a stem mounted on said shank extending above said head having a cap mounted thereon terminating in an annular lower edge and a stop on the periphery thereof below said cap, an ejection spring abutting the lower edge of the head sleeve and a sleeve slidable on said 90 stem between said cap and stop.
9. A separable button, comprising a pair of male and female coacting members, the female member comprising a base, a hollow shank and a head having a central socket opening and a U-shaped locking spring member non-rotatably contained therein, and the male member comprising a base, a hollow shank, a head having a central opening and an annular sleeve projecting downwards therefrom slidable on said shank, a stem mounted on said shank extending above said head having a cap mounted thereon terminating in an annular lower edge and a stop on the periphery thereof below said cap, and a sleeve slidable on said stem between said cap 100 and stop.
10. A separable button, comprising a pair of male and female coacting members, the female member comprising a base, a hollow shank and a head having a central socket opening and a locking spring member non-rotatably contained therein, and the male member comprising a base, a hollow shank, a head having a central opening and an annular sleeve projecting downwards therefrom slidable on said shank, a stem mounted on said shank extending above said head having a cap mounted thereon terminating in an annular lower edge and a stop on the periphery thereof below said cap, and a 110 sleeve slidable on said stem between said cap and stop.

- 6 sleeve slidable on said stem between said cap and stop.
11. A separable button, comprising two cooperating male and female members, 5 having means thereon to lock said members on insertion of the stem of the male member within the socket of the female member and means thereon operable on pressing together and releasing of said members in a 10 true axial line to release said locking means to permit separation thereof.
12. A separable fastener, comprising two cooperating male and female members, the female member having means adjacent to 15 the female portion thereof to lock the stem of the male member therein on insertion thereof, and the male member having means mounted thereon operable to release said locking means in the female member, to 20 permit separation thereof on pressing together in a true axial line and releasing of said members.
13. A separable fastener, comprising two cooperating male and female members, the 25 female member having spring locking means adjacent to the female portion thereof of adapted to register in a groove in the stem of the male member on insertion thereof to lock said members together, and 30 the male member having slidable means mounted on the stem thereof, adapted to close said groove to permit separation of said members on pressing together thereof, and an ejection spring mounted therein to 35 assist in retaining said members together and in the separation thereof.
14. A separable fastener, comprising two cooperating male and female members, the female member having spring locking 40 means adjacent to the female portion thereof of adapted to register in a groove in the stem of the male member on insertion thereof to lock said members together, and the male member having slidable means 45 mounted on the stem thereof, adapted to close said groove to permit separation of said members on pressing together thereof.
15. A separable fastener, comprising two cooperating male and female members, the 50 female member having spring locking means adjacent to the female portion thereof of adapted to register in a groove in the stem of the male member on insertion thereof to lock said members together, and the male member having slidable means 55 mounted on the stem thereof, adapted to close said groove to permit separation of said members on pressing together thereof, and an ejection spring mounted therein to 60 assist in retaining said members together and in the separation thereof, said button being provided with telescoping portions to permit relative pressing together of the members thereof.
16. A separable fastener, comprising two 65 cooperating male and female members, the female member having spring locking means adjacent to the female portion thereof of adapted to register in a groove in the stem of the male member on insertion thereof to lock said members together, and the male member having slidable means mounted on the stem thereof, adapted to close said groove to permit separation of said members on pressing together thereof, said button being provided with telescoping portions to permit relative pressing together of the members thereof. 70
17. A separable button, comprising a pair of male and female coacting members, the female member having a base at one end thereof, and a socket opening at the opposite end thereof, and spring locking means adjacent said socket opening, the male member having a base at one end thereof, a rigid stem projecting therefrom having an enlarged head and telescoping sections surrounding said stem terminating in a head section below said stem head, an expulsion spring abutting said base and telescoping head section and a sleeve slidable on said stem limited in its downward movement and in its upward movement by said enlarged stem head. 75
18. A separable button, comprising a pair of male and female coacting members, the female member having a base at one end thereof, and a socket opening at the opposite end thereof, and spring locking means adjacent said socket opening, the male member having a base at one end thereof, a rigid stem projecting therefrom having an enlarged head and telescoping sections surrounding said stem terminating in a head section below said stem head and a sleeve slidable on said stem limited in its downward movement and in its upward movement by said enlarged stem head. 80
19. A separable button, comprising a pair of male and female coacting members, the female member having a base at one end thereof, and a socket opening at the opposite end thereof, and spring locking means adjacent said socket opening, the male member having a base at one end thereof, a rigid stem projecting therefrom having an enlarged head and telescoping sections surrounding said stem terminating in a head section below said stem head, an expulsion spring abutting said base and telescoping head section and a sleeve slidable on said stem limited in its downward movement and in its upward movement by said enlarged stem head having an annular ridge projecting therefrom substantially centrally of the periphery thereof. 85
20. A separable button, comprising a pair of male and female coacting members, the female member having a base at one end thereof, and a socket opening at the opposite 90

end thereof, and spring locking means adjacent said socket opening, the male member having a base at one end thereof, a rigid stem projecting therefrom having an enlarged head and telescoping sections surrounding said stem terminating in a head section below said stem head and a sleeve slidable on said stem limited in its downward movement and in its upward movement by said enlarged stem head, having an annular ridge projecting therefrom substantially centrally of the periphery thereof.

21. A separable button having a member, having a base, a rigid shank section mounted thereon, and a relatively telescoping head section slidably mounted on said rigid shank section.

22. A separable button having a member, having a base, a rigid shank section mounted thereon, a relatively telescoping head section slidably mounted on said rigid shank section and an ejection spring abutting the base and the lower edge of said telescoping head section.

23. A separable button having a member, having a base, a rigid hollow shank section mounted thereon, a relatively telescoping hollow head section slidably mounted on said rigid shank section, an ejection spring abutting the base and the lower edge of said telescoping head section and a rigid stem projecting from the base thereof above said head section.

24. A separable button having a member, having a base, a rigid hollow shank section mounted thereon, a relatively telescoping hollow head section slidably mounted on said rigid shank section, an ejection spring abutting the base, and the lower edge of said telescoping head section, a rigid stem projecting from the base thereof above said head section having an enlarged head and a sleeve slidable on said stem limited in its downward movement and in its upward movement by said enlarged stem head.

25. A separable button having a member,

having a base, a rigid hollow shank section mounted thereon, a relatively telescoping hollow head section slidably mounted on said rigid shank section, an ejection spring 50 abutting the base and the lower edge of said telescoping head section, a rigid stem projecting from the base thereof above said head section having an enlarged head and a sleeve slidable on said stem limited in its downward movement and in its upward movement by said enlarged stem head and having an annular ridge projecting therefrom substantially centrally of the periphery thereof.

26. A separable button having a member, having a base, a rigid shank section mounted thereon, a relatively telescoping head section slidably mounted on said rigid shank section, a rigid stem projecting from the base thereof above said head section having an enlarged head and a sleeve slidable on said stem limited in its downward movement and in its upward movement by said enlarged stem head.

27. A separable button having a member, having a base, a hollow shank mounted thereon, terminating in a head having a central opening, a rigid stem projecting from the base thereof above said shank head having an enlarged head and a sleeve slidable on said stem limited in its downward movement and in its upward movement by said enlarged stem head.

28. A separable button having a member, having a base, a hollow shank mounted thereon, terminating in a head having a central opening, a rigid stem projecting from the base thereof above said shank head, having an enlarged head and a sleeve 85 slidable on said stem limited in its downward movement and in its upward movement by said enlarged stem head, having an annular ridge projecting therefrom substantially centrally of the periphery thereof.

In testimony whereof I affix my signature.

PAUL J. BELLAVANCE.
